PIVOTED REVERSIBLE WINDOW WITH LATERALLY AND TRANSVERSELY SHIFTABLE PIVOT

John P. Travis, Dallas, Tex.

Application February 16, 1955, Serial No. 488,496

4 Claims. (Cl. 189—66)

This invention relates to a reversible, pivotally mounted window with transversely shiftable pivot, and more particularly to a window which is so pivoted that it may be swung through an angle of three hundred and sixty degrees, and to a method of operating same.

This application is a continuation-in-part of my co-pending application, Serial No. 487,175, filed February 9, 1955, entitled Gyrating and Sliding Pivot Window With Retractable Weather Bar.

One of the principal objects of the invention is to provide a window that may be swung inside out, so that both sides may be cleaned from the inside of the building and still maintain anti-leakwise reveals, and in which the window requires no frame.

A further object of the invention is to provide a window in which the pivotal axis may be shifted with respect to the sides of the grid of the facade in which the window is mounted.

An additional object is to provide a window which may be repaired or cleaned on both sides without the use of scaffolding.

An additional object is to eliminate the necessity for a window frame and to close and/or seal the window against the grid of the facade of a building.

A still further object is to provide a shiftable pivot for a window, such that the pivot may be moved so that danger of striking partitions or fins is avoided during swinging movement.

Yet another object is to provide a rectangular window that may be rotated 180° or 360° through a rectangular opening which is smaller in one dimension than the corresponding dimension of the window.

These and other objects will appear hereinafter in the following specifications, which, taken with the accompanying drawings, constitutes a complete disclosure of the invention.

In the drawings:

Figure 1 is a horizontal section through my improved window just above the top edge of the lower sash rail;

Figure 2 is a view similar to Figure 1, showing the window shifted slightly to the right and showing one movement of the pivot;

Figure 3 is a view similar to Figure 1, showing an additional shift of the pivot and the swinging or rotating of the window in counter-clockwise direction;

Figure 4 is a view similar to Figure 1, showing the window turned 180° and in interfering position;

Figure 5 is a view similar to Figure 1, showing the window and its pivot shifted to the left to clear the fins;

Figure 6 is a view similar to Figure 1, showing in solid lines the window and its pivot swung to substantially closed position and in dotted lines the window shifted to sealing position; and

Figure 7 is a fragmentary vertical section through my window showing the retractable sealing means at the head and sill.

Referring now to the drawings, in which like reference characters indicate like parts throughout the several

2

figures, A represents an opening in the facade B of a building in which a suitably glazed window sash 10 is pivotally and slidably mounted. 12 represents an arm pivoted on the window stool at 14. A similar arm 16 is pivoted at 18 on the head of the window opening. Arms 12 and 16 extend across the opening slightly more than half way and are provided at their outer ends with grooves 20 and 22, respectively.

The upper and lower portions of the sash of window 10 are provided, respectively, with pivots 24 and 26 engaging in grooves 20 and 22, respectively. These pivots are slidable in grooves 20 and 22 for a purpose which will appear hereinafter.

The facade of the building includes grid elements 28 subdividing the bays thereof. Outside the grid members are the fins 30. My window is adapted to fit against the faces of the grid members and to rotate in an opening of less transverse width than that of the window sash. Further, my window joins anti-leakwise reveals by engaging sealing means 32, which may be suitable gasket material applied to grid members 28.

Further to seal the sash, the sill and head are provided, respectively, with retractable bars 34 and 36 adapted to slide in slots 38 and 40, respectively. Bars 38 and 40 are provided with seals 42, which may be suitable gasket material applied to the bars. The bars may be moved to or from operative position either manually or by suitable mechanical means. The means for retracting the bars is not a part of this invention.

This window is especially adapted for use in situations wherein the window of my aforementioned prior application will not operate. In some instances, fins, mullions, partitions, or grid members will not permit the sash to clear when operated as in my aforementioned prior application. To overcome these difficulties, the present device operates in the manner now to be described.

Assuming that the window is in closed position as in Figures 1 and 7, with the sash rails 11 and 13 engaging seals 32 and with seals 42 engaging bottom rail 15 and top rail 17, sealing bars 34 and 36 are retracted, into channels 38 and 40, respectively, to positions in which they will clear rails 15 and 17. The sash is then shifted to the right as seen in Figure 1 to the position shown in Figure 2. Arms 12 and 16 are then moved outwardly, and window 10 is rotated counter-clockwise, as shown in Figure 3, through an angle of 180°.

The outward movement is on the order of 25% to 30% the width of the window, so that the window rotates in the grid opening.

Inward movement of arms 14 and 16 and sliding movement of window 10, with further inward swinging movement of arms 14 and 16, brings the window to the position shown in solid lines in Figure 6, and a sliding movement to the dotted line portion of Figure 6 brings the rails 11 and 13 into facewise engagement with seals 32. Bars 34 and 36 may now be returned to normal position, as shown in Figure 7, engaging the faces of rails 15 and 17. The window is now sealed to form anti-leakwise reveals, and, after cleaning, may either be left in this position or returned to the position of Figure 1 by the operations just set forth.

The window of this invention requires no frame other than the grid members which comprise the facade of the building.

The above description and drawings disclose a single embodiment of the invention, and specific language has been employed in describing the several figures. It will, nevertheless, be understood that no limitations of the invention are thereby contemplated, and that various alterations and modifications may be made such as would occur to one skilled in the art to which the invention relates.

I claim:

1. A reversible window sash adapted to seal facewise against certain of the grid members composing the facade of a building and forming a rectangular grid opening two opposite sides of which constitute window jambs, one dimension of said grid opening being smaller than the corresponding dimension of the window sash, comprising a pair of arms longer than half the window sash width at the head and stool of the grid opening, said arms each being pivoted at one end adjacent one grid member, and having confronting grooves at their other ends, a window sash having pivots midway of its width pivotally and slidably mounted in said grooves, said grooves in normal position extending either side of the center line of the grid opening, whereby said window sash may be shifted in its plane to clear a grid member, then pivoted outwardly by means of the arms and rotated through an angle of one hundred eighty degrees in the opening.

2. A reversible window sash adapted to seal facewise against certain of the grid members composing the facade of a building which form a rectangular grid opening two opposite sides of which constitute window jambs, and in which the window sash is larger in one dimension than the grid opening, comprising grid members including confronting channels, said window sash having side por-

15

tions in facewise engagement with said grids in said channels, a pair of arms pivoted one at the head and the other at the stool adjacent one grid member and substantially longer than half the width of the grid opening, said arms having confronting grooves in the other ends thereof, said grooves in normal position extending either side of the center line of the grid opening, said window sash having upper and lower pivots slidably and rotatably mounted in said grooves, whereby said window sash may be slid in its own plane to clear a grid member, then moved outwardly on its arms and rotated through an angle of one hundred eighty degrees in the grid opening, and then slid in its plane and swung to closed position in facewise sealing engagement with the grids, within the channels.

3. The window sash of claim 1, wherein retractible seals are provided at the head and stool thereof.

4. The window sash of claim 2, wherein retractible seals are provided at the head and stool thereof.
